US00D898738S

(12) **United States Design Patent** (10) Patent No.: **US D898,738 S**
(45) Date of Patent: ** *Oct. 13, 2020

(54) **HEADSET WITH VISOR**

(71) Applicant: **Microsoft Corporation**, Redmond, WA (US)

(72) Inventors: **Nicolas A. Denhez**, Seattle, WA (US); **Young Duk Song**, Kirkland, WA (US); **YeongKyu Yoo**, Bellevue, WA (US); **Paul A. Bosveld**, Seattle, WA (US); **Carl J. Ledbetter**, Mercer Island, WA (US); **Yuenkeen Cheong**, Sammamish, WA (US); **Michael Bohan**, Maple Valley, WA (US); **Lynda Horton-Jones**, Kirkland, WA (US); **Roy Riccomini**, Saratoga, CA (US); **Jason Paul Williams**, Santa Clara, CA (US); **Andriy Pletenetsky**, Mountain View, CA (US); **Joel B. Jacobs**, Seattle, WA (US)

(73) Assignee: **Microsoft Corporation**, Redmond, WA (US)

(*) Notice: This patent is subject to a terminal disclaimer.

(**) Term: **15 Years**

(21) Appl. No.: **29/681,174**

(22) Filed: **Feb. 22, 2019**

(57) **CLAIM**

The ornamental design for a headset with visor, as shown and described.

DESCRIPTION

FIG. 1 is a top front perspective view of a headset with visor showing our new design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depicting of the remainder of the headset with visor in FIGS. 1-8 show features that form no part of the claimed design.

1 Claim, 8 Drawing Sheets
